UNITED STATES PATENT OFFICE.

ALBERT E. JOHNSON, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING ON SOLES.

1,213,770.

Specification of Letters Patent. Patented Jan. 23, 1917.

Application filed March 3, 1913. Serial No. 751,895.

To all whom it may concern:

Be it known that I, ALBERT E. JOHNSON, a citizen of the United States, residing at Beverly, in the county of Essex and State of Massachusetts, have invented certain new and useful Improvements in Machines for Operating on Soles; and I do hereby declare the following to be a full, clear, and exact description of the invention, such as will 10 enable others skilled in the art to which it appertains to make and use the same.

This invention relates to machines for making soles and more particularly insoles used in the manufacture of boots and shoes.

15 The insole blank produced by the machine of the present invention may be utilized for various types and kinds of insoles used in the manufacture of boots and shoes, but it has been found to be particularly useful 20 in making what is known as "Economy" insoles, the single lipped type of which is illustrated and described in the present inventor's United States Letters Patent No. 656,842, dated August 28, 1900, and the double 25 lipped type of which is illustrated and described in the present inventor's United States Letters Patent No. 849,245, dated April 2, 1907.

The single lipped type of "Economy" insole 30 is prepared for reinforcing, that is, the operation of applying the reinforcing material to the insole, from a sole shaped blank, by cutting one face of the blank outwardly within its edge to form a flap parallel to 35 the edge. The flap is turned up at right angles to the cut face of the blank to form an upright rib around the shank and forepart of the insole. As thus prepared, a sheet of reinforcing material is stuck 40 roughly on the blank and the blank and sheet are then passed through a reinforcing machine. If has been the practice heretofore, after channeling the insole blanks, to turn up the flap, by hammers, rotary 45 lip-turning tools, or other means, using pressure alone. It was found, however, that a flap turned to the position shown in Letters Patent No. 656,842, by the pressure devices hereinbefore referred to, has a tendency 50 to droop toward its original position over the channel, especially when the blank is cut from the poorer grades of stock used for reinforced insoles. When this happened, in preliminarily applying the sticky sheet 55 of material to the sole it adhered to the

outer surface of the flap. Under such conditions the tools of the reinforcing machine are prevented from working the reinforcing material down into its proper position in the angle between the channel and the inner surface of the flap, as will be readily recognized by those skilled in the art. The double lipped type overcame the objection just referred to as the uniting of the flap to a marginal lip cut parallel thereto held it securely in its upright position, preventing an exposure of its outer surface to the sticky surface of the reinforcing material and permitting a proper action of the reinforcing machine on the sole. In this 60 type after the flap and lip have been turned up at right angles to the cut face of the blank they are united by cement and pressure, or stitches. Substantially four steps are taken in preparing for reinforcing the 65 double lipped type of insole described in Letters Patent No. 849, 245, namely: the step of edge slitting and channeling the step of lip and flap turning, the step of cement applying, and the step of pressure applying. The use of cement adds to the cost 70 of the insole and the operation of cement applying involves the use of special apparatus. In certain grades of the leather used, such as "splits," cement has been 75 found to be ineffective to permanently secure the flap and lip together and prevent a drooping or partial return of the flap to its position against the face of the sole and for this reason a line of stitching is now 80 generally used to secure the flap and lip together. This also involves the use of special machinery.

The object of the present invention is to produce a machine by which the marginal 85 flap or rib of a sole blank may be permanently set in upturned position, a result heretofore found impracticable.

To the accomplishment of this object a feature of the present invention contemplates the provision in a machine provided with means for supporting and feeding a sole blank having a marginal flap or rib, of means, other than mere pressure applying devices, for treating the flap or rib in a 100 manner to insure a permanent set. It has been discovered that such a result can be secured by stretching the fibers of the material in the flap or rib at the upper marginal portion thereof to produce a length 105 110

at this portion greater than the length at its base. Stretching the fibers so that the length of the upper up-turned edge of the flap or rib is greater than the length at its base, 5 stiffens the rib and permanently sets it in its up-turned position. Its former tendency to droop toward the face of the insole is thus effectually overcome.

Broadly considered the fibers of the upper marginal portion of the up-turned flap 10 or rib may be stretched in any suitable manner found desirable or expedient. It is preferred, however, to produce such stretching by the employment of means for providing 15 the marginal flap or rib with a series of transverse crimps or corrugations.

The provision of crimping or corrugating means forms an important feature of the 20 present invention and is equally advantageous in making any type of insole in which it is desirable to produce an upstanding marginal abutment. In employing this feature of the invention in making the double lipped type of "Economy" insole the crimps 25 or corrugations perform the function of cohesively molding the flap and lip together in a manner to set them in a mutually supporting relation, thus producing from the two a single, substantially upright rib to 30 which the upper and welt may be secured. The union thus obtained is equally as effective as though either cement or stitches were used while the disadvantages attendant upon the use of either of these uniting 35 means are obviated. Obviously an important economy in the manufacture of insoles is effected by the use of the present invention. Those skilled in the art will understand, however, that while it is preferred to 40 set the flap and lip of blanks for "Economy" and like insoles in upturned position without the use of an extraneous binding agent, the arrangement of tools in the machine is not prohibitive of the use of such an agent, 45 if its use is thought desirable.

In its broader aspects the invention contemplates the provision of any suitable crimping or corrugating instrumentalities. It is preferred, however, to employ rolls, 50 constructed and arranged to operate upon opposite sides of the flap or rib and suitably formed to produce the crimps or corrugations therein.

In addition to the features of the invention above referred to other features of the invention consist in certain devices, combinations and arrangements of parts fully set forth hereinafter, the advantages of which will be readily understood by those skilled 55 in the art.

While the invention is hereinafter described and illustrated, for ease of explanation, as operating upon a blank for making the double lipped type of "Economy" insole, 60 it will be obvious to those skilled in the art

that the machine may also be successfully employed in operating upon blanks for making reinforced soles of any other type. As a matter of fact the machine is not limited in its application to operation upon sole 70 blanks for reinforced work, but is equally useful in connection with any sole blank having a marginal rib or abutment, such as solids which it is desired to set permanently in upturned position.

The various features of the present invention will be best understood by an inspection of the accompanying drawings illustrating the best form of the invention at present devised, in which,

Figure 1 is a front elevation of the head of the machine; Fig. 2 is an enlarged detail in front elevation of the operating instrumentalities; Fig. 3 is a plan of a blank showing the manner in which the marginal flap and lip are turned up and set, and also the greater length possessed by the upper upturned marginal portion of the flap than by its base; Fig. 4 is an enlarged detail in left side elevation of the operating instrumentalities; Fig. 5 is a detail in longitudinal sectional elevation of the sole rest, and the feeding and crimping rolls; Fig. 6 is a sectional detail on the line 6—6, Fig. 5; Fig. 7 is a sectional detail on the line 7—7, Fig. 5; and Figs. 8 and 9 are enlarged details in front elevation, partly in section, of the crimping or corrugating rolls.

The machine illustrated in the drawings is provided with two sets of devices engaging the blank, the first set being constructed and arranged to support and feed the blank and the other set being constructed and arranged to operate upon the blank. The devices for supporting and feeding the blank comprise a rotatable sole positioning roll arranged, also, to bend or dish the marginal portion of the sole, a toothed feed roll arranged to engage the channel and a frustoconical feed roll arranged to engage the feather. The devices for operating upon the blank comprise a pair of plows arranged respectively to turn-up the flap and lip, a pair of rolls arranged to operate upon opposite sides of the rib, formed on the illustrated blank by the turned-up flap and lip, a pair of presser feet arranged to engage the opposite sides of the blank in advance of the operating point, and a vertical plate arranged to prevent the curling up of the blank as it is fed from the rolls.

In the illustrated embodiment of the invention the unchanneled face of the blank is engaged by a sole positioning roll 1 having a peripheral bulge 2 at its middle. The roll 1 is rotatably mounted on a vertical stud 3 which is adjustably secured by a set screw 4 to the upper end of a supporting arm 5. The lower end of the arm 5 is journaled on a rod 6 carried by a bracket 7

formed on the machine head. To hold the roll 1 firmly pressed against the unchanneled face of the sole the arm 5 is pivotally connected to one end of a link 8 the other end of which is connected through a tension device to the machine head. This tension device comprises a disk 9 secured to a concentric pin 10 which is rotatably mounted upon the machine head. Coiled around the pin 10 and having one end attached to the link 8 and the other end to the disk 9 is a spring 11. The tension of this spring may be adjusted by rotating the disk 9 which is then held in adjusted position by a nut 12 on the pin 10. The position of the roll 1 under the influence of the spring 11 is limited by an adjustable stud 12^a carried by the arm 5 and arranged to engage a fixed part of the machine head.

20 The devices for feeding the blank comprise a toothed feed roll 13 arranged to engage the channel of the blank and a frustoconical serrated roll 14 arranged to engage the feather (Fig. 5). The roll 13 is provided with a shank 15, shrunk into a hollow roll holder 16 which is secured by a screw 17 to one end of a horizontal shaft 18 journaled in bearings formed in an arm or carrier 19 which is pivotally mounted at 20 on the machine head. The roll 14 is provided with a threaded shank 21 which is received within a hollow roll holder 22 detachably connected to one end of a horizontal shaft 23 journaled in fixed bearings in the machine head. In order to lock the holder 22 in position on the shaft 23 the end of the shaft is provided with a slit 24 (Fig. 9) and with an interiorly threaded chamber 25 arranged to receive a screw 26. By manipulation of the screw 26 through the open end of the holder 22 the end of the shaft 23 may be expanded to lock the holder on the shaft. To drive the shafts 18 and 23 to feed the blank (in the direction of the arrow Fig. 4) the shaft 23 carries a belt driven pulley 27 and the two shafts are rotatably connected through the gears 28. The gear on the shaft 18 is smaller than the gear on the shaft 23 in order that the smaller roll 13 may be driven at the same surface speed as the larger roll 14.

55 The devices for setting the flap and lip of the illustrated insole blank comprise a roll 29 arranged to engage the flap and a roll 30 arranged to engage the lip when these two parts are in up-turned position. The roll 30, which is formed on the roll holder 22, is provided upon its periphery with a series of teeth 31 herein shown as 60 fourteen in number. These teeth have a uniform thickness throughout their length and are slightly rounded at their juncture with the roll 14. The roll 29, which is formed on the roll holder 16, is provided 65 upon its periphery with a series of teeth 32,

herein shown as ten in number, arranged to intermesh with the teeth 31.

By inserting the rib, formed by turning up the flap and lip, between the rolls 29 and 30 and driving the feed rolls 13 and 14 the 75 point of operation of the rolls 29 and 30 is transferred along the rib throughout its length and they thus produce in the rib a series of transverse crimps or corrugations. By forming transverse crimps or corrugations in the flap the fibers of the leather are stretched and a length is produced at its upper up-turned margin which is greater than the length at its base, as may be seen from Fig. 3. This increase in length of the 80 flap stiffens it to such an extent as to permanently set it and its former tendency to droop toward the face of the blank is overcome. As shown in Fig. 4 the roll 29 is smaller than the roll 30. This construction 85 permits the rolls to travel freely around the reverse curves of the blank, as the blank is being fed through the machine.

In order to compress the up-turned flap in the direction of its height to consolidate 90 the fibers of the flap at its base, and thus increase the stiffness of the flap, the ends of the teeth 32 at their juncture with the roll 13 are given the shape of an ogee curve and the teeth 32 also are longitudinally 95 wedge-shaped the thinner ends of the teeth being at their ends adjacent the feed roll 13 (see Figs. 5 to 8). With this construction as the blank is fed through the machine the fibers of the flap are pushed in the 100 direction of the height of the flap and consolidated at its base (Fig. 5).

In order to preliminarily lift or partially turn-up the flap and lip of the illustrated insole blank for the action thereon of the 105 crimping rolls the machine head carries a pair of plows 33 and 34. The plow 33 is provided with a curved portion 35, to permit it to operate closely adjacent the roll 29, and is formed on the depending end of a 110 bent arm 36 the horizontal portion of which is adjustably connected by a slot and screw connection 37 (Fig. 2) to a support 38 on the arm 19. The plow 34 is also provided with a curved portion 39, to permit it to operate 115 closely adjacent the roll 30, and is mounted for adjustment longitudinally of the roll 30, upon a horizontal arm 40 carried by a support 41 vertically adjustable on the machine head. The adjustment on the machine head 120 adapts the plows to different thicknesses of between substances.

In order to grip the opposite sides of the blank in advance of the operating point to prevent the edge of the blank being drawn 125 between the rolls by the natural inward pull of the rolls 29 and 30 the machine is provided with a pair of presser feet 42 and 43. The presser foot 42 is formed on the upper end of a resilient blade 44, arranged 130

on the sole positioning roll supporting arm 5, so that it projects slightly in advance of the sole engaging surface of the sole positioning roll 1 (Figs. 1 and 2). The presser foot 43 consists of a roll which is rotatably mounted upon the upper end of a bent lever 46 centrally pivoted on a lug on the plow support 41. The lower end of the lever 46 is pivotally connected by a link 47 to the arm 5. The other end of the link 47 is connected by means of a coiled spring 48 to the machine head. The lever 46 is provided with an adjustable set screw 45 which abuts against the forward side of the lug to which the lever is pivoted and thus determines the forward position of the presser foot 43 with relation to the crimping rolls under the influence of the spring 48. The connection of the forward end of the link 47 to the arm 5 is through a slot permitting the roll 1 to bear firmly upon the unchanneled face of the insole after the set screw 45 has been seated. This slot also permits the in and out movement of the roll 1 relative to the crimping rolls, as the blank is fed through the machine, due to the uneven thickness of the blank in different parts, without disturbing the position of the foot 43.

In order to prevent the blank from curling as it leaves the crimping rolls the arm 5 carries a vertical plate 49 at the rear of these rolls (Fig. 4) which engages the unchanneled face of the blank in the line of feed and holds the blank straight as it is fed from the machine.

To permit the unobstructed insertion of a blank into and its removal from the machine the devices for supporting, feeding and operating upon the blank are mounted for relative separation at the will of the operative. To this end the sole positioning roll supporting arm 5 carries an integral arm 50 (Fig. 1) which is provided at its upper end with a yoke 51 the arms of which embrace a block 52 pivotally mounted on a pin 53. The pin 53 is carried by an arm 54 secured to a rock shaft 55 journaled in the machine head. A second arm 56 secured to the shaft 55 is connected at its free end to a treadle rod 57 the lower end of which is connected to the usual treadle on the machine base. Depression of the treadle by the operative swings the roll 1 to the left (Fig. 1) away from the unchanneled face of the roll. As the arm 5 swings outwardly the link 46 is drawn forward, against the tension of the spring 48 to tip the lever 46 and remove the roll 43 from the channeled face of the blank. To simultaneously separate the feeding and crimping rolls, to release the crimped rib, the shaft 55 carries a third arm 58 the upper end of which engages a foot 59 secured to the arm or upper tool carrier 19. As the shaft 55 is rocked by the depression of the treadle by the operative the rolls 13 and 29

are elevated against the tension of a coiled spring 60 interposed in a chamber in a bridge piece 61 on the machine head, between the top of the arm 19 and the lower end of a rod 62 adjustably carried by the bridge.

As the blanks operated upon are tempered before insertion into the machine of the drawings it is desirable to heat the crimping rolls to insure the permanency of the set imparted to the rib by the rolls. To this end the machine head adjacent the rolls is provided with a steam chamber 62^a which is provided with an intake 63 and an outlet 64 both of which are adapted to be connected to a steam circulating system.

From the foregoing description it will be seen that an important feature of the present invention is in providing means for retaining the marginal abutment on a sole in its desired upstanding position, it being immaterial how such an abutment is produced or of what substance it is made so long as the material is such that it will receive the crimps or corrugations.

It will also be seen that another important feature of the invention resides in the provision, in a machine for making a single, compound lip or rib from a flap and lip formed on an insole, of rotary rolls, for acting on the rib, and means for preliminarily lifting, or partially upturning, the flap and lip for the action of said rolls, whatever the nature of the action of said rolls on the rib may be.

For the reasons hereinbefore set forth the invention is not limited to the details of construction and operation of the illustrated embodiment nor to the conjoint use of all its features, but may be embodied in other forms within the terms and spirit of the claims, in which characterizing features are set forth by the intentional use of generic terms and expressions inclusive of various modifications.

What is claimed as new is:—

1. A machine for operating upon a sole blank having a marginal flap or rib, having, in combination, means for supporting and feeding the blank, and means for stretching the fibers of the material in the flap or rib at the upper marginal portion thereof to produce a length at this portion of the flap or rib greater than the length at its base to permanently set it, substantially as described.

2. A machine for operating upon a sole blank having a marginal abutment, having, in combination, means for supporting and feeding the blank, and means for providing the marginal abutment with a series of transverse crimps or corrugations to set it in upturned position, substantially as described.

3. A machine for operating upon an insole

5 blank having a flap and a parallel lip on one face, having, in combination, means for supporting and feeding the blank, and means for molding the flap and lip against each other into a configuration providing mutual support one for the other, substantially as described.

10 4. A machine for operating upon an insole blank having a flap and a parallel lip on one face, having, in combination, means for turning up the flap and lip, and means for providing the flap and lip with a series of transverse crimps or corrugations, substantially as described.

15 5. A machine for operating upon a sole blank having a flap on one face, having, in combination, means for turning up the flap, and means for compressing the up-turned flap in the direction of its height to consolidate the fibers of the flap at its base, substantially as described.

20 6. A machine for operating upon a sole blank having a marginal abutment, having, in combination, means for supporting and feeding the blank, and a pair of intermeshing toothed rolls, one larger than the other, for molding the marginal abutment, substantially as described.

25 7. A machine for operating upon sole blanks, having, in combination, means for supporting, feeding and operating upon the blank, and a pair of presser feet arranged to engage the opposite sides of the blank in advance of the operating point, substantially as described.

30 8. A machine for operating upon sole blanks, having, in combination, means for supporting, feeding and operating upon the blank, a pair of presser feet arranged to engage the opposite sides of the blank in advance of the operating point, and means for reversely actuating the presser feet to permit the unobstructed insertion of the blank into and its removal from the machine, substantially as described.

35 9. A machine for operating upon a sole blank having a marginal abutment, having, in combination, a pair of rolls constructed and arranged to engage the marginal abutment with their circumferential surfaces, and means in advance of said rolls in the line of feed for preventing the edge of the blank being pulled inward between the rolls, substantially as described.

40 10. A machine for operating upon a sole blank having a marginal abutment, having, in combination, a pair of rolls constructed and arranged to engage the marginal abutment with their circumferential surfaces, and a presser foot arranged to engage the feather portion of the blank and prevent the edge of the blank being pulled inward between the rolls, substantially as described.

45 11. A machine for operating upon a sole blank having a marginal abutment, having,

in combination, means for supporting, feeding, and operating on the marginal portion of the blank, including a pair of intermeshing toothed rolls for engaging and crimping the abutment between them, substantially as 70 described.

12. A machine for operating upon a sole blank having a marginal abutment, having, in combination, means for supporting, feeding, and operating on the marginal portion 75 of the blank, including a pair of toothed rolls for engaging and molding the abutment, one of said rolls having its teeth tapering in width at the end for engaging the base portion of the abutment, substantially as de- 80 scribed.

13. A machine for operating upon a sole blank having a marginal abutment, having, in combination, means for supporting, feeding, and operating on the marginal portion 85 of the blank, including a pair of toothed rolls for engaging and molding the abutment, one of said rolls having its teeth tapering in width and formed with ogee curves 90 at their ends which engage the base portion of the abutment, substantially as described.

14. A machine for operating upon a sole blank having a marginal abutment, having, in combination, means for supporting, feeding and operating on the marginal portion 95 of the blank including a tool at the inner side of the abutment, a second tool at the outer side of the abutment, one of said tools being provided with one or more concavities in its working face and the other being provided with one or more projections on its working face, and operating means for causing the projections on the one tool to enter the concavities in the other tool thereby to crimp the abutment between them, substan- 100 tially, as described.

15. A machine for operating upon a sole blank having a marginal abutment, having, in combination, means for supporting, feeding and operating on the marginal portion 110 of the blank including a pair of oppositely disposed crimping tools each having alternate projections and depressions in its working face, the projections on one tool being disposed so as to enter coöperating depre- 115 sions in the other tool, and means for guiding the abutment between said crimping tools, substantially as described.

16. A machine for operating upon a sole blank having a marginal abutment, having, 120 in combination, means for supporting, feeding and operating on the marginal portion of the blank including a pair of oppositely disposed crimping tools each having alternate projections and depressions in its working face, the projections on one tool being disposed so as to enter coöperating depre- 125 sions in the other tool, means for actuating one of said tools to effect an intermeshing of said projections and depressions, a swinging 130

- carrier for the other tool, and means for moving said carrier to separate the tools for the insertion and removal of the blank, substantially as described.
17. A machine for operating on an insole blank having a flap and parallel lip on one face, having, in combination, a pair of pressure rolls, one for the flap and one for the lip, having working faces for engaging the flap and lip between them to press said flap and lip into intimate contact, and means in advance, in the line of feed, of said rolls for turning up both the flap and lip for the action of said rolls thereon, substantially as described.
18. A machine for operating on an insole blank having a flap and a parallel lip on one face, having, in combination, means for turning up both the flap and lip, a pair of pressure rolls for pressing and setting the upturned flap and lip into intimate contact, and means engaging the unlipped face of the sole constructed and arranged to hold said flap and lip in position for the action of said rolls thereon, substantially as described.
19. A machine for operating on an insole blank, having a flap and a parallel lip previously cut in one face, having, in combination, a pair of tools acting one inside the flap and the other outside the lip for pressing and setting the flap and lip into intimate contact, plows for preliminarily lifting or partially upturning both the flap and lip for the action of said tools, and means for supporting the blank in operative position with relation to said tools and plows, substantially as described.
20. A machine for operating on an insole blank having a flap and a parallel lip previously cut in one face, having, in combination, tools at both the inside of the flap and the outside of the lip for lifting the flap and lip from the body of the blank and pressing them into intimate contact, a rotary feed wheel for engaging the feather of the blank, and means for supporting the blank in operative position with relation to said tools, substantially as described.
21. A machine for operating on an insole blank having a flap and a parallel lip previously cut in one face, having, in combination, a rotary tool having parts to press against and support the lip and to engage the feather to feed the blank, a lip lifting plow arranged in advance of said wheel, a flap lifting plow and coöperating tool to press against and set the flap in intimate contact with the lip, and means for supporting the blank in operative position with relation to said tools, substantially as described.
22. A machine for operating on an insole blank having a flap and a parallel lip previously cut in one face, having, in combination, a rotary tool having a circumferential surface to press against and support the lip from base to top, a lip plow curved about the lip engaging surface of said tool in advance thereof in the line of feed, a second rotary tool having a circumferential surface to press against and support the flap from base to top and coöperate with said first named rotary tool to set the flap and lip into intimate contact, and means for supporting the sole in position for the operation of said tools, substantially as described.
23. A machine of the character described, having, in combination, crimping tools constructed and arranged for forming a transverse crimp in the lip of a sole, and means for actuating said tools to feed said sole, substantially as described.
24. A machine of the character described, having, in combination, crimping tools constructed and arranged for forming a transverse crimp in the lip of a sole, means for actuating said tools to feed said sole, and means for turning an uncrimped portion of said lip into position to be crimped, substantially as described.
25. A machine of the character described, having, in combination, crimping tools constructed and arranged for forming a transverse crimp in the lip of a sole, and a lip-turning tool to act upon the uncrimped portion of the lip and turn it into position to be crimped by said crimping tools, substantially as described.
26. A machine of the character described, having, in combination, crimping tools constructed and arranged for forming a transverse crimp in the lip of a sole, a device for holding the lip of the sole in position to be operated upon by said tools, and means for withdrawing said device from said tools to facilitate insertion of a sole in a machine, substantially as described.
